UNITED STATES PATENT OFFICE.

RALPH G. JACKSON, OF CHESTER, PENNSYLVANIA, ASSIGNOR TO THE CONGOLEUM COMPANY, OF PHILADELPHIA, PENNSYLVANIA, A CORPORATION OF PENNSYLVANIA.

BLOCK-PRINTING MACHINE.

1,241,391.

Specification of Letters Patent. Patented Sept. 25, 1917.

Application filed November 16, 1916. Serial No. 131,700.

To all whom it may concern:

Be it known that I, RALPH G. JACKSON, a citizen of the United States, and a resident of Chester, county of Delaware, State of Pennsylvania, have invented certain Improvements in Block-Printing Machines, of which the following is a specification.

My invention relates to certain improvements in block printing machines of the type in which the material to be printed is intermittently moved and the carriers, on which the printing blocks are mounted, are intermittently reciprocated so as to make the impression.

15 This invention is an improvement on the patent granted to William H. Waldron, November 21st, 1915, No. 1,115,301, in which the latches for holding the carriers out of action are controlled by cams and rods. The 20 machine of the patent is automatic and the printing blocks are held out of action at predetermined intervals, according to the location of the cams.

One object of my invention is to provide 25 means for releasing any one of the carriers from the control of the automatic mechanism, so that certain blocks can make impressions out of their order.

A further object of the invention is to 30 construct the machine so that sections of a strip, which were previously considered waste, can be utilized to make rugs smaller than the predetermined size being printed on the machine.

35 In the accompanying drawings:—

Figure 1, is a sectional view of sufficient 40 of a block printing machine to illustrate my invention, the section being on the line 1—1, Fig. 2;

Fig. 2, is a sectional plan view on the line 2—2, Fig. 1, with some of the elements removed; and

45 Fig. 3, is a detached perspective view of a portion of the hand operating device to which my invention relates.

1 is the table of a block printing machine mounted on a frame 2. 3 is a spiked endless band which carries the material to be printed over the table. 4 is a carrier for the printing block 5. This carrier consists of two vertical members 6 adapted to guides at the side of the frame 2 and a cross frame 7 connecting the vertical members and to which the printing block 5 is directly attached.

55 8 is a driving shaft having a worm wheel

9 thereon which meshes with a gear wheel 10 on a cam shaft 11 having a cam 12 thereon, shown by dotted lines, for elevating the carrier 4. 13 is a rock shaft having at each end a latch 14 arranged to engage the 60 projecting portion 15 of the carrier 4, and on this rock shaft is a counterweight 16 which tends to throw the latch out of engagement with the portion 15. When the latch is in engagement with the portion 15, the carrier and the printing block are held out of action, but when the latch is withdrawn then it is reciprocated, the cam raising it and its weight lowering it to the printing position.

In machines constructed according to the 70 Waldron patent above alluded to a cam 17 on a driven shaft 18 moves a rod 19 in one direction through the lever 20 and, in the present instance, it acts upon a head 21 on the end of the rod. A spring 22 located 75 between the collar 23 on the rod and a fixed abutment 24 on the frame 2 tends to move the rod in a direction opposite to the cam. On the rod is a collar 24 which comes in contact with an arm 25 on the rock shaft 13 carrying the latches 14. The spring 22 tends to hold the latches 14 in engagement with the portion 15 of the carrier 4, and the cams 17 move the rod against the pressure of the 80 springs and release the latches at certain 85 intervals so as to allow the carrier and the printing block to descend to make an impression.

In machines of this type there is a series 90 of carriers, each controlled by a cam and a rod, and latches. The mechanism is entirely automatic. Therefore, if imperfections occur in the base material and the machine is printing rugs of any size some of these 95 imperfections may occur in the center of a rug otherwise perfect, or even at the edge of a rug, making that entire section worthless.

The main feature of my invention is to 100 provide means whereby the defective portions of the material can be passed through the machine without being printed upon and without interfering with the standard size of the rug.

By my invention, the operator can actuate the mechanism which will allow a border section to be printed out of time and in place of one of the body sections, so that a short rug, less in length than the standard length, will be printed, while the de- 110

fective portion adjoining this short section will be avoided and a rug of standard size will be started immediately after this defective portion has passed the printing 5 point.

Mounted in suitable bearings in the frame of the machine is a rock shaft 26 extending from one side of the machine to the other and having a handle 27 at each end, so that 10 it can be turned by hand from either side of the machine. On the shaft is an arm 28, which is attached to a head 29 on the rod 19, so that, by turning the shaft 26 in the direction of the arrow, Fig. 1, the rod will be 15 moved longitudinally and the spring 22 will be compressed, relieving the rock shaft 18 from the pressure of the said spring and allowing the counterweight 16 to fall, moving the latches 14 away from the projections 20 15 on the carrier, so that each released carrier will then come under the control of the cam 12 and its printing block carried thereon will make an impression out of the predetermined order.

25 There is one of these devices at each carrier and the operator watches the material as it is fed to the machine. If he perceives a defective portion he follows this section throughout the length of the machine and 30 he can gage the printing so that, when the material passes a border block, he can shift the mechanism by turning the rock shaft 26, releasing the carrier and allowing the printing block to make an impression and 35 at the same time he can hold out of action the carrier having the body block thereon, by merely turning a hand lock 30, which bears against one of the latches and holds the rock shaft in the locked position until 40 the material has passed that particular block. The operator follows this defective section until it passes the final printing block. Consequently, if there is a small defective portion in the material and the machine is printing 6x9 rugs, the operator will 45 so adjust the mechanism of the machine that this defective portion will be avoided and a perfect 6x6 rug will be printed. These odd sized rugs are sold at full price per foot, 50 whereas if the rug contained an imperfec-

tion it could not be sold except at a considerable loss.

I claim:—

1. The combination in a block printing machine, of means for intermittently feeding the material through the machine; a printing block carrier; means for lifting the carrier; means for holding the carrier out of action; mechanically operated means for releasing the carrier; and hand operated 60 means for releasing the carrier to be actuated out of time with the mechanically operated means.

2. The combination in a block printing machine of the type having a series of intermittently reciprocating block carriers and means for intermittently moving the material through the machine, of a block carrier; a counter-balanced latch for the carrier; a rod for actuating the latch; a spring 70 for moving the rod in one direction; a cam for moving the rod in the opposite direction; and hand operated means for moving the rod in the same direction as the cam to compress the spring and to release the carrier 75 from the control of the latch.

3. The combination in a block printing machine, of a bed; means for intermittently carrying the material over the bed; a block carrier; means for actuating said carrier to 80 allow the block to make an impression; a latch at the carrier arranged to hold it out of position; a counterbalance for each latch so that when the said latch is released it will move away from the carrier; a rock 85 shaft on which the latch is mounted; an arm on said shaft; an actuating rod having a collar bearing against the arm; a spring for moving the rod in one direction; mechanically operated means for moving the 90 rod in the opposite direction; and a hand operated rock shaft having an arm engaging the rod so that when it is desired to release the carrier and to allow the printing block to make an impression the hand operated rock shaft is turned, causing the controlling rod to move against the pressure of 95 the spring to release the latch.

RALPH G. JACKSON.
